UNITED STATES PATENT OFFICE.

ANTON STEHLE, OF CANNSTADT, GERMANY.

ADJUSTABLE ASSORTING-SCREEN.

SPECIFICATION forming part of Letters Patent No. 436,615, dated September 16, 1890.

Application filed March 29, 1890. Serial No. 345,926. (No model.)

To all whom it may concern:

Be it known that I, ANTON STEHLE, a subject of the King of Würtemberg, residing at Cannstadt, Würtemberg, Germany, have invented a new and useful Improvement in Adjustable Assorting-Screens, of which the following is a specification.

This invention relates to flat screens having parallel wires extending longitudinally of the screen, a portion of which are attached at equidistant points to transverse bars secured to the screen-frame, while another group of wires interposed between the former is also attached to transverse bars, which, by a peculiar arrangement, hereinafter to be described, may be raised or lowered at pleasure, so that the intervals between the wires of the screen may be adjusted and raised between certain limits, all the intervals being equal for any one position of the wires.

In the accompanying drawings, Figures 1, 2, and 4 represent, respectively, a plan, a side elevation, and a transverse vertical section of an adjustable screen embodying my invention; and Figs. 3, 5, 6, and 7, detail views, on an enlarged scale, of the mechanism for raising and lowering the wires.

In the drawings I have shown round wires; but obviously rectangular wires or wires of any desired cross-section may be employed. I have herein shown the first, fifth, ninth, &c., wires d^4 as attached to the transverse rods or bars D^4 , which in turn are secured to the screen-frame S , while the intermediate screen-wires—35 to wit, the second, sixth, tenth, &c., wires d^2 —are attached to the upwardly-movable transverse bars D^2 , the third, seventh, eleventh, &c., wires d^3 to the downwardly-movable transverse bars D^3 , and the fourth, eighteenth, twelfth, &c., wires d' to the upwardly-movable transverse rod D' .

The arrangement for lifting the transverse rods D' and D^2 is such that the same are lifted to the same extent to a certain height, while the transverse carriers D^3 , with their wires d^3 , do not change their position at the start. When the two wires d' and d^2 have been raised so that their mean distance from d^3 and d^4 is equal to that between d^3 and d^4 , and it is desired to obtain still greater intervals between the wires, the wires d' and d^2 must

not only be farther raised, but the wires d^3 , together with the transverse bars D^2 , must be lowered or depressed. The actual sorting or separation is now performed only by the 55 wires d^3 and d^4 , while the wires d' and d^2 are lifted to such an extent as to permit the free passage of the mixture to be separated to the lower screen-wires. For this purpose the screen-wire d' should be raised particularly 60 high. The following arrangement serves to attain all these ends: Of the superimposed transverse bars $D' D^2 D^3 D^4$, carrying the wires d', d^2, d^3 , and d^4 , the bars $D' D^2 D^3$ are bolted to the carriers A', A^2 , and A^3 at both 65 ends, so that by raising or lowering these carriers the screen-wires are also raised or lowered. To prevent any lateral shifting of these carriers they run in guide-grooves S , formed in the four corners of the screen. The 70 bars $D' D^2 D^3$, with the wires d', d^2, d^3 , and the brackets A', A^2, A^3 constitute together the movable screen-frames.

The raising and lowering of the carriers A', A^2 , and A^3 is effected by the instrumentalities shown in detail in Figs. 3, 5, 6, and 7.

The screen-frame S depends from the two supporting-shafts T of the screen by means of the supports or hangers Z . Four cams and disks E are also mounted on the same. These 80 cam-disks E are provided on one side with so-called "lifting-bosses" e' for elevating the carriers of the transverse bars A^2 , while on the other side are located two diametrically-disposed pins carrying rollers r' and r^3 , designed to lift A' and lower A^3 .

The lifting-boss e' of the cam-disk E , when the latter is rotated, impinges against the lower face of a lug on the lifting-bracket a^2 , attached to the carrier A^2 of the transverse 90 bars, lifting the latter, and with it the parts A^2 , the carrier A' , which rests freely on the carrier A^2 , being coincidentally lifted. As soon as a certain height has been attained the point of the boss e' rides under a curved extension of the lug extending from a^2 , whereby no further rise of A^2 is produced upon the further rotation of the cam-disk E . However, the rollers r' and r^3 of the cam-disk E now come into action, the roller r' bearing up 95 against a lug on a bracket a' , rising from the carrier A' , and lifting the latter still farther,

while the roller r^3 presses down upon the depressing-piece on the carrier A^3 , whereby the latter is lowered.

The carrier A^3 is maintained in its normal position by the two springs $P P$, while the carriers A' and A^2 are returned thereto by their own weight and that of their appendages.

In order to insure a perfectly uniform raising and lowering of the screen-wires $d' d^2 d^3$, the four similar cam-disks E occupy exactly the same position on the supporting-shafts T , and their adjustment is carried out by two levers K , connected by rods v . In order to secure these two levers K in a determined position, I provide an arc-shaped bracket B for one of these two levers, the said lever being retained in any position by a pin s , inserted into one of the holes in the bracket B .

In order to facilitate the lifting of the carriers for the transverse bars, together with said transverse bars and screen-wires, which represent a considerable weight in the larger sizes of screens, a horizontal lever H , provided at its end with a counter-weight G , (whose size is adapted to the circumstances of the case,) is attached to one of the axles T . This adjustable assorting-screen works as follows: The mixture to be assorted is poured in uniform thickness upon the sieve while the same is agitated, all of the screen-wires $d' d^2 d^3 d^4$ occupying the same plane, and the spaces between the wires being consequently at a minimum. A particular dumping device is employed for this purpose. The smallest particles now pass through the screen, and after the same have been collected in a receptacle the screen-wires d' to d^3 are raised or lowered at stated intervals by means of the levers K , together with the other described devices. The interstices of the screen are thereby changed and enlarged step by step until the coarsest part of the mixture has passed through. The levers K are thereupon returned to their initial position, so that the smallest spaces are restored. A new supply of the mixture is then poured on and the assorting operation resumed.

The adjustment of the size of the screen-openings may be performed by hand or automatically and intermittently at regular periods.

I claim—

1. In an adjustable assorting-screen, the combination of a fixed screen-frame having screen-wires and movable screen-frames with means for moving a portion of the movable screen-frames upward and another portion downward, substantially as and for the purposes set forth.

2. In an adjustable assorting-screen, the combination of a stationary screen-frame and a movable screen-frame having a bracket extending therefrom with a cam-disk for acting

upon the bracket to elevate the movable screen-frame, all substantially as described.

3. In an adjustable assorting-screen, a fixed screen-frame and a series of vertically-movable screen frames provided with brackets and a spring interposed between one of the movable frames and the fixed frame, in combination with a cam-disk provided with rollers $r' r^2$, all substantially as described.

4. In an adjustable assorting-screen, the combination of a fixed screen-frame and a series of movable screen-frames having upwardly-extending brackets, one of the brackets being provided with a lug having a curved extension, with a cam-disk provided with rollers, as $r' r^3$, all substantially as described.

5. In an adjustable assorting-screen, the combination of the following parts: a fixed screen-frame provided with a hanger, a shaft or axle from which it is suspended, a series of movable screens provided with brackets, a cam-disk having moving devices for engaging the brackets of the movable screen-frames, and a lever attached to the shaft or axle for turning the same and the cam-disk, all substantially as set forth.

6. In an adjustable assorting-screen, the combination of the following parts: a fixed screen-frame provided with a hanger, an axle from which it is suspended, a series of movable screens provided with brackets, a cam-disk having moving devices for engaging the brackets of the movable screens, and a lever attached to the axle for turning the same, and the cam-disk and a retaining-bracket for holding the lever in its various positions of adjustment, all substantially as described.

7. In an adjustable assorting-screen, the combination of the following parts: a fixed screen-frame, two shafts from which the same are suspended, a series of movable screen-frames having brackets, cam-disks attached to the shafts and having moving devices for engaging the brackets, and two levers also attached to the shafts and connected by links, all substantially as set forth.

8. In an adjustable assorting-screen, the combination of the following parts: a fixed screen-frame, two shafts from which they are suspended, a series of movable screen-frames having brackets, cam-disks attached to the shafts and having moving devices for engaging the said brackets, two levers also attached to the shafts and connected by links, and a weighted lever attached to one of the shafts, all substantially as set forth.

In testimony whereof I have signed this specification in the presence of two subscribing witnesses.

ANTON STEHLE.
